WING FRAME FOR STREET SIGNS.

Filed Nov. 29, 1940

UNITED STATES PATENT OFFICE

2,242,331

WING FRAME FOR STREET SIGNS

Abraham Sprung, Brooklyn, N. Y.

Application November 29, 1940, Serial No. 367,682

10 Claims. (Cl. 40—145)

This invention relates to street or other sign holders and more particularly to a wing frame for street signs.

One object of this invention is to provide a cornerpiece with one or more integral holding arms and a sign holding frame for each holding arm, said sign holding frames being vertically insertable in chambers in each holding arm, and means for wedging said frame in its assembled position without the use of bolts and nuts.

Another advantage of the present invention resides in the provision of a wing frame for street signs which will not sag due to the weight of the sign nor become horizontally or vertically displaced.

A still further advantage of the present invention is to completely eliminate the use of bolts, nuts or similar retaining means in the entire assembled construction of the holding frame and holding arms.

Yet another purpose of the present invention is to provide a frame of this character which is easy to manufacture and easy to assemble.

A further aim lies in the provision of a frame of this type which is doubly locked, thus preventing tampering with or the unauthorized removal of the sign.

Still another advantage of this invention is to provide means for securely connecting the holding frame to the holding arms, so as to make it impossible for the frame to become loose due to vibration or wind.

These and other meritorious objects, which will become more fully apparent as this description proceeds, are accomplished by the novel construction and combination of simple parts, hereinafter described and illustrated in the accompanying drawing, forming a material part of this disclosure, and in which:

Figure 1 is an inside elevational view of a street sign constructed according to my invention and showing one sign holding frame in assembled position.

Figure 2 is a sectional view taken on line 2—2 of Figure 1.

Figure 3 is a sectional view taken on line 3—3 of Figure 1.

Figure 4 is a fragmentary front elevational view of a holding arm and holding frame ready to be vertically dropped into the holding arm and showing a vertical key way, parts being broken away to show the inner construction.

Figure 5 is a plan view of the end of the frame engaged in the extension of the holding arm, showing the key pin between both members.

Figure 6 is an inside perspective view of the cornerpiece, one of the sign holding frames being shown as assembled.

Referring in greater detail to the accompanying drawing, the number 10 designates in general a metal post, either tubular or of any other desired cross-section, which is suitably anchored in the ground. Mounted on post 10 is a cornerpiece 11 of the same cross-section as the post 10, and it is adapted to partially encircle said post.

The cornerpiece 11 is formed with two vertical holding arms 12 and 13 arranged in fixed angular relationship to each other. Both arms are of identical construction and are provided with a vertical slot 14 located in horizontally disposed extension pieces 25. The slot 14 provides means for retaining therein the end of a sign holding frame in a manner to be hereinafter described.

The sign holding frame consists of superimposed frame members 15—16, normally riveted together. Each of said members has an opening for the display of a sign, and if desired an additional smaller opening for an additional sign. These openings are indicated at 17 and 18.

The superimposed frame members 15 and 16 are usually riveted together, as at 19, 20, 19', 20', or cast together so as to be permanently united and at the same time leave a space between them for the insertion of a sign plate.

The vertical slot 14 is positioned in the outer end of extension 25. This slot 14 is so arranged, that its opposing walls 21 or 22 or both are in-reaching.

The slots 25 in the upper extensions are through-reaching, while the slots in the lower extensions are provided with stops 26.

Thus, when the frame has been vertically inserted into its assembled position in the extensions, it cannot be displaced horizontally due to the inreaching portions 27—27' and it cannot be displaced vertically due to the stop 25 and wedging key pin 29 which is vertically inserted into key slot 30 in the extension and cooperating key slot 30' in the end of the frame. The walls 21 and 22 may be inreaching in such manner, that a narrower point is reached as indicated at 27 and a wider portion as at 28.

When assembling the street sign frame, it is merely required to drop the ends 31 of the frame into slots 14 of the extension pieces until the lower end of 31 rests on the stop 26. The ends 31, being of the same cross-section as the slots 14, will fit snugly therein. Key pin 28 which is of wedge construction is then vertically forced into the cooperating keyways on the extension and

the outer end of the frame. Forcing the key pin into the key slots will force the ends of the frame against the walls of the slot thereby holding it in rigid position. Clamp bands 23 and 24 are bolted to the cornerpiece when the sign is secured to post 10 so as to form a permanent juncture. The sign holding frame and post engaging cornerpiece are manufactured of malleable iron.

Having thus described the invention, what is claimed as new and desired to secure by Letters Patent, is:

1. A sign holding device comprising a body portion having a horizontally extending holding arm, a sign holding frame, said arm having a vertically arranged groove, said groove provided with a narrower width at its open side, and adapted to receive an end portion of said frame, said end portion having a cooperating contour, a vertical key-way between the walls of said groove and said frame end portion and a wedge in said key-way.

2. A sign holding device comprising a body portion having a horizontally extending holding arm, a sign holding frame, said arm having a vertically arranged groove, said groove provided with a narrower width at its open side and adapted to receive an end portion of said frame, said end portion having a cooperating contour, the opposing walls of the groove and end portion being provided with a vertical key-way, and wedge means disposed in said key-way.

3. A sign holding device comprising a body portion having a horizontally extending holding arm, a sign holding frame, said arm having a vertically arranged groove, said groove provided with a narrower width towards its open side and adapted to receive an end portion of said frame, said end portion having a cooperating contour, a vertical key-way between opposing surfaces of the groove and said end portion, and a pin engageable in said key-way.

4. A sign holding device comprising a post engaging cornerpiece, an arm extending from said cornerpiece, said arm being formed with a vertically arranged groove, a sign holding frame having an end portion disposed in said groove, said groove having a vertical inreaching wall portion spaced from back of said groove, said frame end portion having a cooperating contour, the opposing surfaces of the groove and end portion being formed with a vertical key-way, and wedge means engageable in said key-way.

5. A sign holding device comprising a body portion having a holding arm, a sign holding frame, said arm having a vertically arranged groove, said groove provided with a narrower width at its open side, formed with an opening at its upper end for vertically receiving an end portion of said frame, said end portion having

a cooperating contour, the opposing walls of the groove and end portion formed to provide a vertically arranged key-way, and wedge means disposed in said key-way.

5. A sign holding device comprising a post engaging cornerpiece, a holding arm provided with a pair of vertically spaced horizontal extensions having vertically arranged grooves, each of said grooves having a narrower width at its open side, a sign holding frame having one end disposed in said grooves, said end having a side wall of cooperating contour, one of said extensions provided with a vertical key-way between the walls of said groove and said frame end, and a pin disposed in said key-way.

7. A sign holding device having a horizontally extending holding arm, a sign holding frame, said arm having a vertically arranged groove, said groove provided with an inreaching wall portion spaced from the back of said groove, said groove open at its upper end and closed at its lower end, said sign holding frame having an end portion of cooperating contour engageable in said groove, the opposing walls of said groove and end portion being formed to provided a vertically arranged key-way, and a wedge means disposed in said key-way.

8. A sign holding device comprising a body portion having a horizontally extending holding arm, a sign holding frame, said arm having a vertical groove, said groove provided with an inreaching wall portion spaced from the back of said groove for receiving an end portion of said frame, said end portion having a cooperating contour, a vertical key-way between opposing surfaces of said groove and said end portion, and a wedge means engageable in said key-way.

9. A sign holding device comprising a body portion having a horizontally extending holding arm, a sign holding frame, said arm having a vertically arranged groove, said groove having a dove-tail cross section adapted to receive an end portion of said frame, said end portion having a cooperating contour, a vertically arranged key-way between the walls of said groove and said frame end portion, and a wedge means in said key-way.

10. A sign holding device comprising a body portion having a horizontally extending holding arm, a sign holding frame, said arm having a vertical groove, said groove having a narrower width at its open side and open at its upper end, an end portion of said frame disposed in said groove, said end portion having a cooperating contour, a downwardly arranged key-way between opposing surfaces of said groove and end portion, and a wedging means engageable therein.
